TENT

Rutcher Skagerberg, St. Paul, Minn.

Application November 19, 1930
Serial No. 496,596

23 Claims. (Cl. 135—1)

This invention relates to tents and to correlated subject matter, and has for its primary object the provision of a tent structure which is economical of manufacture, which can be easily set up and transported, and which furnishes an effective shelter.

Another object of the invention is to provide a tent structure of the character under consideration which has the maximum of sturdiness commensurate with the provision of a tent which can be economically manufactured and readily transported and set up.

A further object is to provide a structure which gives a maximum of shelter in relation to the total area of the material of which it is composed.

Another object is to provide an improved method of forming a tent.

Still another object is to provide an improved type of package whereby a tent of the character under consideration may be transported.

Other objects of the invention will in part be obvious and will in part appear hereinafter.

The invention accordingly comprises an article of manufacture possessing the features, properties and the relation of elements which will be exemplified in the article hereinafter described and the scope of the application of which will be indicated in the claims.

For a fuller understanding of the nature and objects of the invention, reference should be had to the following detailed description taken in connection with the accompanying drawings, in which:

Fig. 1 is a perspective view of one form of tent such as contemplated by the invention;

Fig. 2 is a plan view of the blank from which the tent is formed;

Fig. 3 is a plan view of a slightly modified form of blank;

Fig. 4 is a perspective view of a tent formed from the blank of Fig. 3;

Fig. 5 is a view of a blank and reinforcements adapted for use in the provision of a tent with a reinforced doorway edge;

Fig. 6 is a plan view of the assembled blank;

Fig. 7 is a sectional view along the line 7—7 of Fig. 6;

Fig. 8 is an enlarged sectional view along the line 8—8 of Fig. 6;

Fig. 9 is a front view of a tent formed from the blank of Fig. 6;

Fig. 10 is a plan view of a blank having additional reinforcements;

Fig. 11 is a plan view of a slightly modified

form of blank equipped with reinforcements for the doorway edges of a tent;

Fig. 12 is an enlarged sectional view along the line 12—12 of Fig. 11;

Fig. 13 is a front view of a tent formed from the blank of Fig. 11;

Fig. 14 shows the blank of Fig. 11 rolled into a package for transportation;

Fig. 15 shows still another modified form of blank; and

Fig. 16 is a perspective view of a tent formed from the blank of Fig. 15.

The invention primarily has in view the provision of a tent which may be so economically manufactured and may be sold at so low a price as to render available to the general public a form of shelter for purposes where tents of ordinary construction have found no general utilization, as well as the provision of a form of tent which may be so readily erected and taken down as to avoid the necessity for the user to have any particular skill or workmanship to erect or remove the same, and which will occupy less space in transportation than ordinary hand luggage. These and other ends may be attained in accordance with the invention by the provision of a tent formed from a suitably-shaped blank of semi-rigid material, such, for example, as paper-board, which is rigid enough to support itself when set up in tent form, and which is nevertheless sufficiently flexible so that the erecting operation can be readily performed, or in certain instances, by the provision of a suitably-shaped blank of hingedly-connected relatively rigid sections, such for example, as folded, stiff, paper-board.

Among the various semi-rigid materials which may be utilized, are various types of paper-board, linoleum, strip roofing materials, building felt, etc.

The blank from which the tent is to be formed is preferably composed of a single sheet of material, suitably reinforced if necessary, but it will be understood that the blank may be composed, in certain instances, of several pieces of material connected together in any desired manner, as for example, when scrap materials are to be utilized.

It has been found that a particularly satisfactory shape of blank for the purpose in hand is a semi-circle truncated at one side, which, when gathered together about a point at the center of the imaginary circle of which the blank forms a part, provides a tent which is generally cone-shaped, having an opening at one side corresponding to part of the portion of the semi-circle which has been cut away. A similarly truncated

half of a regular polygon will, when similarly gathered together, provide a pyramidal tent, which possesses similar characteristics. It will be appreciated, moreover, that in certain instances blanks whose edge line varies from a true arc in other manners, may be utilized. For the sake of facility of expression the terms "generally semi-circular", generally arcuate, and the like, are utilized to describe all forms of half circles and modified half-circles, arcs and modified arcs, etc.; and the term "generally cone-shaped" is utilized to describe structures such as cones or pyramids, or similar forms, and such terms are to be so understood.

15 A few of the many wide varieties of possible embodiments of the invention are illustrated by way of example. There is exemplified in Fig. 2 a blank 20 of suitable semi-rigid material, which, as will be seen, is shaped to conform with a semi-circle truncated on a line perpendicular to its edge-diameter and disposed some distance outwardly from its perpendicular radius. When this blank is bent at the center of the geometric circle of which it forms a part and its right-angle corner 21 moved past the diametric edge at the other side of the blank, will form a cone-shaped structure admirably adapted for use as a tent, as will be seen from Fig. 1. The structure there shown will be self-supporting when the corner 21 is suitably secured in place, can be easily entered through the doorway provided between its diametric edge and the edge at which it is truncated, and will provide satisfactory protection for one or more persons, dependent upon the size of the blank. In order to secure the corner 21 in place, the blank is preferably perforated as indicated at 22 and 23, and a removable fastener 24 or other suitable fastening means, passed through these openings when the same are aligned. It is to be observed that the blank thus provided may be shipped flat, either alone or in quantity, or may be rolled, and in either event will require an unusually small space. It can also be very easily formed into a tent by a user having no knowledge of how an ordinary tent should be securely erected.

In Fig. 3 there is exemplified a slightly modified form of blank indicated at 25. A tent formed therefrom is shown in Fig. 4. It is to be observed that the blank 25 is truncated on a line somewhat farther from the center of its circle, whereby there is provided a tent having a greater enclosed area and a lower doorway. A fold line 26 is provided at the inner edge of the folded-over corner 25 or flap 27 of the tent to facilitate the assembly of the tent. There are also provided along the curved edge of the tent a plurality of openings 28 through which stakes 29 may be driven into the ground. Eyelets 28' may be provided at these openings, and also at the fastening openings 30 and 31, for the purpose of preventing tearing of the material.

In certain instances, and particularly when the blank is formed of light paper-board, it is found desirable to reinforce those edges of the blank which outline the doorway of the tent when the same is assembled, as well as to provide, in certain instances, a reinforcement of the outer edge of the flap. To this end the blank may be formed in the manner indicated in Fig. 5, wherein the material from which the blank is formed is extended beyond the normal straight edges of the blank in the manner indicated at 36, 37 and 38, and these extended portions folded over and suitably secured against the body of the blank. The

tent may also be provided, when desired, with reinforcing strips, such as indicated at 39 and 40, which may be fitted within folded portions so as to further reinforce the edges of the blank where necessary. It is to be observed in connection with the strip 39 that this strip, as well as the corresponding portions of the blank, is formed with openings 41 through which removable fasteners 42 may be inserted on assembly so that the blank may be shipped or carried in the form of a roll in a manner which will be more particularly brought out in connection with Fig. 14.

80 In the reinforcing strip 40, there is provided a bend 40' at the point where the strip 40 crosses the strip 39 in the assembly of the tent. This permits the overlapping portion to be flat against the tent wall.

85 There is also exemplified in connection with the blank shown in Figs. 5 and 6, a recess indicated at 43, whereby the folding of the blank to form the tent is facilitated. With such a recess provided, the likelihood of formation of a regular fold-line adjacent the apex of the tent, whereby the strength of the tent at this point may be 90 weakened, is eliminated.

95 In some cases, as where the blank is made of particularly light material, it is desirable to provide stiffening reinforcements on its body. Figure 10 exemplifies a blank 44 provided with a stiffening strip 45, as well as with its stiffening strips 46, 47 and 48, which reinforce its portions. These strips may be secured in any suitable manner, as by gluing, stapling, clamping, for example. If openings for the reception of stakes are provided, these may conveniently extend 100 through the reinforcing strips, as indicated at 49, so as to reduce the possibility of tearing.

105 In Fig. 11 there is shown a form of blank provided with edge reinforcements which does not require folding over of the material of which the body of the blank is composed. To this blank 50 there is permanently secured to its shorter straight edge, as by gluing, a reinforcing strip 51, and has detachably secured to its radial edge, as by means of removable fasteners, a reinforcing strip 52. There is also glued, or otherwise 110 secured, on the overlapping corner 53, a flat, triangular piece of reinforcing material 54, which serves to prevent tearing at a point which is particularly subject to tearing action. The blank 50 is formed with a recess 55 similar to the recess 43 in the blank 35. Fig. 13 shows the blank set up in the form of a tent with stakes 56 extending through openings 57. It is to be observed that the outer openings 57 extend through the reinforcing strips.

115 By removably mounting the reinforcing piece along the radial edge of the blank, it is possible readily to roll a blank such as shown in Fig. 11 (or one such as shown in Fig. 5) into a package having no greater length than the radius of a circle defining the edge of the blank. In forming such a package the removable strip such as 52 is laid adjacent the permanent strip 51. Auxiliary pieces such as fasteners, stakes, etc. are laid 120 beside it and the blank rolled upon these pieces into a compact package such as indicated in Fig. 14. Although this package will require a relatively small amount of space, it nevertheless can be formed without cracking ordinary paper board. The package may be suitably tied in rolled position or may be enclosed in a paper covering as indicated in 59 in Fig. 14.

125 In Fig. 15 there is exemplified a blank which is in the form of half a regular octagon, trun-

cated at 61 and adapted to be bent along radial lines 62, 63 and 64 in the formation of a tent. The blank in this instance is formed with an outwardly-extending portion 65, against which edge portion 66 is adapted to be secured by a suitable fastener as indicated at 70 when the tent is erected. The portion 66 is preferably reinforced by bending over an outwardly-extending portion of the blank, as is also the edge portion 67 beyond the portion 65. When desired, the portion 65, the areas adjacent the fold lines 62, 63 and 64, and the area adjacent the edge 61 may be suitably reinforced by strips of material as indicated. These strips of material may be cloth, stiff paper, flexible paper board, adhesive tape, or any other desirable material. Likewise, additional reinforcements at each side of the tent may be provided as indicated at 68, 69 and 70.

There may also be provided, if desired, a suitable floor for the tent which may be generally circular in shape and formed of paper-board, balsa wool, linoleum, or other suitable material which preferably is sufficiently flexible to be rolled with the blank for transportation.

It will thus be seen that there is provided an inexpensive and readily set-up form of tent which requires no poles or ropes to keep its shape, which can be utilized as a play tent for children, a temporary sun shelter on beaches and the like, a temporary shelter for dogs, and which is so easily portable that it is well adapted for use as a night shelter on short automobile trips where there is neither space to carry, nor time to assemble, an ordinary type of tent. Because of its portability and relatively light weight a tent made in accordance with the invention is also well adapted for use by campers. A tent made of paper-board, for example, because of its inexpensive construction, can, when desired, be destroyed after use, or when wet, so that the difficulties attendant to the transportation of a tent from a beach or camp site are avoided.

Since certain changes may be made in the above article and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having described my invention, what I claim as new and desire to secure by Letters Patent, is:

1. A tent shaped to provide a generally conical enclosure having a doorway and comprising a single blank of material sufficiently rigid to be self-supporting without the use of poles and sufficiently flexible to be spread out flat, to be gathered into tent form or to be rolled into a package by the user, and removable means for securing the tent in erected position, said means being disposed sufficiently above the base to permit entry into said tent.

2. A tent comprising a self-supporting generally cone-shaped structure formed of a single blank of material generally semi-circular in shape with one corner cut away to provide a doorway and means to secure said blank in erected position.

3. A tent comprising a self-supporting blank of semi-rigid material generally semi-circular in shape with one end cut away and gathered upon

itself to provide the apex of the tent at a point approximating the center of a circle defining the generally arcuate edge of the flat blank and to provide a doorway opening where the cutaway portion would have been, and means to secure said blank in erected position.

4. A tent comprising a self-supporting blank of semi-rigid material generally semi-circular in shape with one end cut away on a line parallel to its perpendicular radius and gathered into tent form with the apex of the tent at a point approximating the center of a circle defining the generally arcuate edge of the flat blank, and with a doorway provided where the cutaway portion would have been.

5. A tent comprising a blank of semi-rigid material generally semi-circular in shape and cut away adjacent one corner, said blank being gathered upon itself to form a generally cone-shaped structure with a doorway opening in the place where the cutaway portion of the semi-circle would have been.

6. A tent comprising a self-supporting blank and means to secure said blank in erected position, said blank being gathered upon itself to provide a doorway one edge of which is defined by a line substantially perpendicular to the lower edge of the tent and the other edge of which is defined by a line extending obliquely from the aforesaid line at a point considerably below the apex of the tent to the lower edge of the tent.

7. A tent comprising a blank of semi-rigid material generally semi-circular in shape with one corner cut away, said blank being gathered into tent form about the point where its radii converge, whereby its truncated edge radius is disposed adjacent its other edge radius and a doorway opening is provided at the place where the cutaway portion would have been.

8. A tent formed of semi-rigid material generally semi-circular in shape when laid out flat and cut away on a line parallel to its perpendicular radius, a reinforcing strip secured along the edge at which the material is cut away, a reinforcing strip removably secured to said material along its radial edge a portion of which defines a doorway.

9. A tent-forming blank generally semi-circular in shape and having one corner cut away and folded upon itself on a line adjacent the edge at which it is cut away, and also folded upon itself on a line adjacent its diametric edge whereby the blank is reinforced adjacent these edges which defines the doorway of the erected tent.

10. A tent formed from a blank of semi-rigid material generally semi-circular in shape with one corner cut away, said blank being gathered upon itself to form a generally cone-shaped structure with a door-way opening, and having a plurality of holes along its generally arcuate edge for the reception of stakes and means to secure said blank in erected position.

11. A tent formed from a blank of semi-rigid material generally semi-circular in shape with one corner cut away, said blank being gathered upon itself to form a generally cone-shaped structure with a door-way opening, and reinforcing elements extending upwardly from the lower edge of the tent, said blank being formed with a plurality of holes along its generally arcuate edge, at least certain of said holes extending thru said reinforcing elements and means to secure said blank in erected position.

12. A tent formed from a blank of semi-rigid material generally semi-circular in shape with

one corner cut away, said blank being gathered upon itself to form a generally cone-shaped structure with a door-way opening, a portion of the truncated half of said blank overlapping the other half and being secured in place there-against.

13. A tent comprising a self-supporting blank generally semi-circular in shape with one corner cut away, said blank being bent upon itself at a point in proximity to the center of a circle defining the generally arcuate edge of the flat blank, and having a portion of the truncated quadrant secured in overlapping relation to the other quadrant so as to provide a generally cone-shaped

15. structure having a door-way, one edge of which is defined by the diametric radius of the blank and other edge of which is defined by the line of truncation.

14. A tent comprising a semi-circular blank 20 truncated at one corner and composed of semi-rigid material, said blank being bent upon itself into conical form with its arcuate edge defining the base of the cone, so that its truncated edge defines one edge of a doorway, and means to secure said blank in such position.

15. A tent comprising a blank of semi-rigid material shaped to correspond to half of a regular polygon with one of its acute-angle portions cut away, said blank being folded into the form of a 30 pyramid, with the truncated edge defining one side of a doorway opening, and means to secure said blank in such position.

16. A tent-forming blank, comprising a generally semi-circular piece of semi-rigid material cut away adjacent one corner and adapted to be gathered upon itself to form a generally cone-shaped structure with a doorway opening in the place where the cutaway portion of the semi-circle would have been.

40 17. A tent-forming blank, comprising a piece of self-supporting material generally semi-circular in shape and cut away adjacent one corner, said piece of material being adapted to be gathered into a cone-shaped structure and shaped to form, when so gathered, a doorway, one edge of which is defined by a portion of the diametrical edge of the piece, and the other edge of which is defined by the line of cutting away, and elements adapted to reinforce said edges.

50 18. A tent comprising a generally cone-shaped structure and means for securing various portions of said structure and formed of material

55

sufficiently rigid to be self-supporting without the use of poles and sufficiently flexible to be spread out flat, a portion of said material being cut away to provide a door.

19. A tent comprising a generally cone-shaped structure formed of self-supporting sheet material which is sufficiently flexible to be spread out flat, and fastening means securing the sheet material in erected position without the use of poles, said fastening means being positioned to permit access to said tent at a point directly above the base.

20. A tent comprising a generally cone-shaped structure formed of self-supporting sheet material, which is sufficiently flexible to be spread out flat, and fastening means securing the sheet material in erected position without the use of poles with the apex of the cone substantially above the center of its base, said fastening means being positioned to permit access to said tent at a point directly above the base.

21. A tent comprising a generally cone-shaped structure formed of self-supporting sheet material which is sufficiently flexible to be spread out flat, and fastening means securing the sheet material in erected position without the use of poles, said fastening means being positioned to permit access to said tent at a point directly above said base and a portion of said sheet material being cut away to provide a small opening at the top of the structure.

22. A tent comprising a generally cone-shaped structure formed of self-supporting sheet material which is sufficiently flexible to be spread out flat, fastening means securing the sheet material in erected position without the use of poles with the apex of the cone substantially above the center of its base, said fastening means being positioned to permit access to said tent at a point directly above said base, and a generally circular floor member of flexible material disposed at the base of the cone.

23. A tent comprising a generally cone-shaped member and means for securing various portions of said structure and formed of material sufficiently rigid to be self-supporting without the use of poles and sufficiently flexible to be spread out flat, one edge of said material providing the base and another edge providing the side of the door.
